UMBRELLA HANDLE FOR HOLDING RUBBERS, SANDALS, OR OVERSHOES

Ruth G. Halstead, New York, N. Y.

Application February 16, 1939, Serial No. 256,639 1/2

11 Claims. (Cl. 135—47)

This invention relates to umbrella handles for holding rubbers, sandals or overshoes.

Prior devices of this character according to Marsh Patent No. 1,859,627 and McWilliams Patents Nos. 1,931,078 and 2,044,251 have comprised merely an enlarged handle for the umbrella, provided with a single chamber large enough to receive therein both overshoes rolled up together. This has required that the overshoes be carefully rolled before insertion, to produce a roll small enough to enter the chamber. Furthermore the tractive effect of the rubber engaging the inner wall of the chamber has rendered the insertion difficult unless the roll has been sufficiently smaller than the chamber to allow a satisfactory clearance. If the chamber were made large enough to receive a pair not carefully rolled, and also provide clearance against friction, the outer diameter of the handle would be undesirably large for convenient grasp by the hand.

The rolling up of the two overshoes together into a roll of the compactness necessary renders it practically essential to have a flat bearing surface, such as a table top, to work on, but inasmuch as the device is intended for outdoor use, such surface is seldom available. Also the overshoes to be rolled are those which have been used and are generally damp or soiled.

Furthermore, the storage of the two overshoes rolled up together necessitates both overshoes being removed in order to release either of the pair. This results in the disadvantage of having to hold the second overshoe in the hands long with the umbrella and the receptacle cover, while the first is being put on for wear. Here again in outdoor use there is seldom available a convenient rack or support, on which to rest excess articles.

The main objects of the present invention therefore are to avoid these disadvantages, and to provide a receptacle with separate storage for the respective overshoes of a pair, whereby either overshoe may be removed from the receptacle and put on for wear without disturbing the other stored overshoe, and also to provide storage which will receive the respective overshoes in haphazard collapsed condition, without requiring special rolling or other preparatory operation.

Other objects and features of novelty will be apparent as the following description proceeds, with reference to the accompanying drawing, in which

Figure 1 is a side elevation of the device according to one embodiment of the present invention, one side being broken away and shown

in section to expose the collapsed overshoe therein; and

Figure 2 is a top plan view of the same, but shown with the cover rotated to open position; and the overshoes removed.

In one form of the invention, as shown in the drawing, the receptacle consists of two hollow cylindrical members constituting recesses or chambers 4 and 6, each adapted to receive therein, in collapsed or folded condition, one member 10 of a pair of overshoes, one of such overshoes of the pair being designated by the reference numeral 5 in Fig. 1 of the accompanying drawing. In this form of the invention, the cylindrical members are disposed side by side and in substantially parallel, spaced relation, with a finger space 12 therebetween, and constitute spaced chambers or grips 7 and 8, each of which is open at the top and closed at the bottom.

The hollow cylindrical chambers or grips 7 and 8 may be made from tubular stock of any suitable metallic or non-metallic material, and in the form shown in the drawing, the bottoms of each member 7 and 8 are closed by caps 4' and 6' connected by a brace or tie 9 provided with a depending boss 14 by means of which the receptacle may be secured to a staff or stem 15 shown in the drawing, as being the stem of an umbrella 16. The bore of the depending boss 14 and the stem 15 may be threaded, if desired, as shown, but any other means for securing the receptacle to the umbrella may be employed. The upper ends of the two hollow cylindrical chambers or grips 7 and 8 are provided with annular flanges 4'' and 6'', respectively, connected by a brace or tie 10. While I have elected to illustrate the receptacle as consisting of two tubular chambers or grips 7 and 8 closed at their bottoms by caps 4' and 6' and provided at their tops with annular flanges 4'' and 6'', it is to be understood that it is not essential that this identical construction be employed, and that the receptacle may, if desired, be constructed of suitable molding material, either metallic or non-metallic, in which event the cylindrical members or grips 7 and 8, bottom caps 4' and 6', the braces or ties 9 and 10 and the top annular flanges 4'' and 6'' would all be included as an integral structure.

A cover is provided for closing the open upper ends of the chambers or grips. This cover comprises two lobes 17 and 18 of each a diameter approximately the same as the diameter of each of the annular flanges at the tops of the chambers or grips, and a connecting portion 19 pref-

erably of the same shape as the brace or tie 10. The cover is pivoted on the body preferably by a pivot pin 20 centrally mounted on the brace 10 and passing through the center of the cover 5 portion 19. If desired projections 21 may be formed on the cover, to enter dimples 22 formed in the brace 10, to lock the cover in closed position, but this is not essential, because friction between the parts may be sufficient for practical 10 purposes.

With the parts in the open position shown in Figure 2, the overshoes are readily inserted into their respective chambers, and the cover rotated to the position shown in Fig. 1. Due to the 15 finger space 12 between the grips 7 and 8, either of these grips may be grasped to support the umbrella in open or closed position, raised or lowered. Also, the closed umbrella may be supported by a finger passing under the brace 10. 20 Also, the raised umbrella may be supported by the handle with the cover resting in the palm of the hand, and either a finger or a thumb passing over the brace 10.

When it is desired to put on the overshoes 25 for wear, the cover can be readily rotated to open the receptacle. This can even be done with only one hand, by a sidewise movement of the thumb of the hand which is grasping either of the hollow portions 7 or 8. The other hand can then 30 remove one of the overshoes and put it on for wear, the other overshoe remaining stored out of the way. Or the cover may be closed after each overshoe is removed, and the hand grasping the umbrella handle may be moved over the 35 cover, to employ the umbrella staff as a cane to maintain the equilibrium of the wearer, while the respective overshoes are being put on.

Of course, if the overshoes are to be put on 40 while the umbrella is raised, the receptacle is in inverted position, but the friction of the rubber is generally sufficient to prevent either overshoe from accidentally falling out even while the cover is open, but not enough to interfere with ready intentional removal.

45 When the wearing of the overshoes is no longer desired, they may be restored one at a time in the order in which they are taken off. The separate chamber for each overshoe provides ample room so that the overshoe can be 50 pushed in, being collapsed in an indiscriminate or haphazard or even careless fashion. This can be done with only the finger tips engaging the overshoe.

55 While one embodiment of the invention has been shown and described in detail, it is obvious that various modifications will be readily apparent to those skilled in the art. The invention therefore is not limited to the details disclosed, but embraces such embodiments of the broad 60 idea as fall within the scope of the appended claims.

I claim:

1. An article of manufacture comprising a pair of hollow members respectively forming 65 individual receptacles for receiving one overshoe of a pair, said members each having an entrance aperture through which its respective overshoe may be inserted, in combination with means for holding said members each spaced 70 from the other to form a finger space therebetween whereby either of said members may be grasped by the hand.

2. An article of manufacture comprising, a handle having a recess therein adapted to receive 75 in collapsed condition one overshoe of a pair,

said handle having a second recess spaced from the first recess to form a finger space therebetween, said second recess adapted to receive in collapsed condition the other overshoe of the same pair, and means pivoted on an axis between said recesses for closing the same and retaining said collapsed overshoes therein. 5

3. An article of manufacture comprising a shank and a handle, said handle being provided with two separate and spaced recesses each 10 adapted to respectively receive one overshoe of a pair, and means pivoted on said handle between said recesses and extending radially from said pivot in different directions over said recesses to close the same, thereby forming an individual container for each overshoe of the pair, said handle having a bore aligned with said pivot and in which an end of said shank is secured. 15

4. An article of manufacture comprising a pair 20 of open ended members each adapted to receive in collapsed condition one overshoe of a pair, a rigid member near the open ends of said members holding the same in spaced relation to form a finger space therebetween, and a cover for both 25 members pivoted on said rigid member, said cover when in open position extending between said open ends.

5. A hand-carried accessory comprising a pair 30 of grips each having a recess adapted to respectively receive therein in collapsed condition one overshoe of a pair, a rigid brace connecting said grips and holding them apart to form a finger space therebetween, and a cover for each recess 35 mounted on said accessory and adapted to permit separate withdrawal of each overshoe without disturbing the other, whereby the grip storing said other overshoe may be grasped while the withdrawn overshoe is being put on for wear. 40

6. A hand-carried accessory comprising a pair 45 of grips each having a recess adapted to respectively receive therein in collapsed condition one overshoe of a pair, a rigid brace connecting said grips and holding them apart to form a finger space therebetween, and a cover pivoted on said brace between said recesses and adapted to simultaneously open said recesses to permit separate withdrawal of each overshoe without disturbing the other, and to simultaneously close 50 said recesses whereby said brace and cover may be grasped together while the withdrawn overshoe is being put on for wear.

7. A portable accessory comprising a shank terminating at one end in a portion adapted to engage the ground and terminating at the other 55 end in an enlarged portion provided with two separate hollow grips each adapted to respectively receive one overshoe of a pair and to permit separate withdrawal of each overshoe without disturbing the other, and a brace spacing 60 said grips and forming a finger space therebetween, whereby the grip storing said other overshoe may be grasped by the hand and the other end of said shank rested on the ground to serve as a staff to support the wearer while the withdrawn overshoe is being put on. 65

8. An article of manufacture having a base provided with a central depending boss and a pair of spaced upstanding symmetrical hollow cylindrical portions thereabove, a brace connecting the upper ends of said cylindrical portions, and a cover pivoted on said brace coaxial with said boss and having oppositely disposed portions extending over the respective cylinders. 70

9. An article of manufacture having a base 75

provided with a central depending boss and a pair of spaced upstanding symmetrical hollow cylindrical portions thereabove each adapted to respectively receive one overshoe of a pair, a brace connecting the upper ends of said cylindrical portions and holding them spaced apart to form a finger space therebetween, and a cover pivoted on said brace coaxial with said boss and having oppositely disposed portions extending over the respective cylinders and adapted to permit separate withdrawal of either of said overshoes without disturbing the other, and a staff secured in said depending boss whereby said article may serve as a cane to support the user grasping said brace and cover as a handle.

10. An article of manufacture comprising a body portion having a recess therein adapted to

receive in collapsed condition one overshoe of a pair, said body portion having a second recess adapted to receive in collapsed condition the other overshoe of the same pair, said second recess having its longitudinal axis out of alignment with the longitudinal axis of the first mentioned recess to form a finger space between said recesses, and means for retaining said overshoes in their respective recesses in collapsed condition.

11. A hand carried accessory comprising a pair of spaced grips each having a recess adapted to respectively receive therein in collapsed condition one overshoe of a pair, and a rigid brace connecting said grips and holding them apart to form a finger space therebetween.
